UNITED STATES PATENT OFFICE

137,930

DESIGN FOR A HEAD FOR A LAWN MOWER

Earl L. Schofield, Auburn, Ind., assignor to Atwood Vacuum Machine Company, Rockford, Ill., a copartnership composed of Seth B. Atwood and James T. Atwood

Application October 9, 1943, Serial No. 111,325

Term of patent 14 years

(Cl. D40—1)

To all whom it may concern:

Be it known that I, Earl L. Schofield, a citizen of the United States, residing at Auburn, in the county of De Kalb and State of Indiana, have invented a new, original, and ornamental Design for a Head for a Lawn Mower, of which the following is a specification, reference being had to the accompanying drawing forming part thereof.

In the drawing:

Fig. 1 is a top plan view of a head for a lawn mower showing my new design, a ground roller being indicated in dotted lines, and

Figs. 2 and 3 are, respectively, front and rear perspective views of the head on a reduced scale, showing the reel in dotted lines in both views, and also showing the cutter-bar and ground roller in dotted lines in Fig. 3.

The essential features of the design are shown in full lines on the drawing.

I claim:

The ornamental design for a head for a lawn mower, substantially as shown and described.

EARL L. SCHOFIELD.
